UNITED STATES PATENT OFFICE.

EDWARD J. PAQUE, OF CINCINNATI, OHIO, ASSIGNOR TO THE POLLAK STEEL COMPANY, OF CINCINNATI, OHIO, A CORPORATION OF OHIO.

APPARATUS FOR FORMING FORGINGS.

1,352,911.

Specification of Letters Patent. Patented Sept. 14, 1920.

Application filed August 1, 1919. Serial No. 314,696.

To all whom it may concern:

Be it known that I, EDWARD J. PAQUE, a citizen of the United States of America, and a resident of Cincinnati, in the county of 5 Hamilton and State of Ohio, have invented a new and useful Improvement in Apparatus for Forming Forgings, of which the following is a specification.

My invention relates to a method and apparatus for forming objects, of varying diameter and with external walls which are located in various planes, from a piece of stock metal which is of substantially uniform diameter and with practically vertical 15 external walls.

My invention relates particularly to the formation of gear blanks from cylindrical pieces of metal.

The object of my invention is a process 20 and apparatus by which the external corners of the articles may be made sharp and uniform.

This and other objects are attained by the means described in the specification and 25 illustrated in the accompanying drawings, in which:—

Figure 1, is a perspective view of a press embodying my invention and by means of which the process embodying my invention 30 may be performed.

Fig. 2, is a perspective view of a piece of stock metal from which the article is formed.

Fig. 3, is a perspective view of a gear blank, which may be formed in the apparatus illustrated in Fig. 1.

Fig. 4, is a central sectional view upon an enlarged scale of the upper and lower dies, the stop block, the punch and the stripper embodying my invention.

Fig. 5, is a view similar to Fig. 4, but showing the gage block removed.

Fig. 6, is a view similar to Figs. 4 and 5, but showing the strippers in the position which they occupy in stripping the punch 45 from the articles.

Fig. 7, is a view similar to Fig. 6, but showing the position of the parts which they assume in the removal of the article from the bottom die.

The apparatus embodying my invention 50 comprises upper and lower dies A, B, punch D, removable stop block E, and a press upon the base F of which the lower die is mounted

and by the upper platen F' of which the upper die and the punch are carried. The 55 lower die has in it a central recess b, which communicates with a central bore b', which is of the diameter of the stem k of an ejector whose head k' seats in the bottom of the recess b and forms with the walls thereof 60 a die chamber which is of the shape of the lower part of the article H.

Below the bore b' the die member B has a T slot b² upon the shoulders of which a pin k² of ejector arm k³ is adapted to seat. 65 Upon the opposite sides of the die B there are pivotally mounted U shaped arms M which are adapted to engage the upper die member A in the act of stripping the punch and the upper die from the article which 70 has been formed.

The upper die A has in it a central recess a and a central bore adapted to fit over the punch D. When the punch is in its retracted position, as shown in Fig. 7, its end forms 75 with the walls of the upper die a die chamber which is the complement of the die chamber formed by the upper face of the ejector and the walls of the recess b, so that when the upper and lower dies are in contact with each other these die chambers form a chamber of the shape of the article to be formed.

Upper die A is suspended from the platen F' by means of chains a' and punch D is 85 carried by the platen. Between the platen and the upper die the removable stop block E is adapted to be seated surrounding the punch. When the removable stop block is between the upper die and the shoulder d 90 of the punch, the lower end of the punch is seated in the bore of the upper die and is either flush with the upper face of the upper die chamber or else projected slightly beyond it.

In carrying out my process, the upper die being raised and the stop block being inserted between the shoulder d and the upper die, a piece of stock metal, such as the cylindrical piece H', having been placed so that its lower end rests within recess b and on the ejector k', the platen F' is lowered until the upper die A contacts with the lower die B, this will cause the metal to be formed into a blank which resembles that of the finished article with the exception

that the corners thereof are left in a rounded unfinished condition, such as shown in Fig. 4. Then removable stop block E is removed and the die punch D is lowered so that it forms a central recess in the article to be formed and the metal thus displaced from the center of the article forces the metal at the rounded corners of the article outward so as to fill the spaces in the die, so as to 10 form sharp and uniform corners upon the article. Then the strippers M are placed in engagement with the upper die, as shown in Fig. 6, and the platen is raised. This will cause the punch and the upper die to be separated from the article and to eject the article which falls into the bottom of the press. To eject the article therefrom lever k^3 is actuated.

Having thus described my invention, 20 what I claim is:

1. In an apparatus for forming metal the combination of a lower die member having a recess conforming to the shape of the walls of a part of the article to be formed, 25 an upper die member having a central recess and adapted to coöperate with the recess in the lower die member to form a die chamber of the shape of the article to be manufactured, a punch seated in the recess in the 30 upper die member and a removable stop block adapted to hold the punch in a retracted position.

2. In an apparatus for forming metal forgings the combination of upper and 35 lower die members having coöoperating recesses which form a die chamber of the shape of the article to be formed, a punch reciprocally mounted in one of the die members and adapted to force a recess in the 40 article to be manufactured, and strippers

mounted upon one of the die members and adapted to engage the other die member.

3. In an apparatus for forming metal forgings the combination of upper and lower die members, having recesses therein 45 adapted to form a die chamber of the shape of the article to be formed, a punch reciprocally mounted in one of the die members, an ejector mounted upon the other die member and strippers mounted upon one die 50 member and adapted to engage the other die member.

4. In an apparatus for forming metal forgings, the combination of upper and lower die members having recesses adapted 55 to form a chamber of the shape of the article to be formed, a punch passing through the upper die member and into the chamber, and a removable stop block adapted to fit between the upper die member and a 60 shoulder upon the punch.

5. In an apparatus for forming metal forgings the combination of upper and lower die members having recesses therein adapted to form a die chamber of the shape 65 of the article to be formed, the lower member having a downwardly projecting bore communicating with its recess, a punch reciprocally mounted in the upper die member, an ejector having a head seated upon 70 the bottom of the recess in the lower die member, the upper face of the head forming the lower wall of the die chamber and having a stem projecting downwardly through the bore, and a lever pivoted in the lower 75 die member and contacting with the stem.

In testimony whereof I have hereunto subscribed my name this 31st day of July, 1919.

EDWARD J. PAQUE.
